UNITED STATES PATENT OFFICE

159,952

IRONING BOARD

Charles Buser, Auburn, N. Y., assignor to Beh and Company, New York, N. Y., a corporation of New York

Application January 29, 1948, Serial No. 144,135

Term of patent 7 years

(Cl. D49—1)

To all whom it may concern:

Be it known that I, Charles Buser, a citizen of the United States, residing at Clark Street Road, Auburn, New York, in the county of Cayuga and State of New York, have invented a new, original, and ornamental Design for an Ironing Board, of which the following is a specification, reference being had to the accompanying drawing, constituting a part hereof.

Fig. 1 is a perspective view of an ironing board embodying my new design.

Fig. 2 is a side view.

Fig. 3 is an end elevational view.

I claim:

The ornamental design for an Ironing Board, substantially as shown.

CHARLES BUSER.
